UNITED STATES PATENT OFFICE.

ERNEST C. MOORHEAD, OF STAMFORD, CONNECTICUT.

APPARATUS FOR MOLDING CORES.

Application filed January 13, 1927. Serial No. 160,838.

The invention relates to the art of producing cores used in the casting of metal and more particularly has to do with the production of cores for use in casting metal 5 elements such as sash weights and metal units of equivalent physical form. Metal elements of the class referred to are provided with means for the accommodation of a suspending connection or its equivalent, 10 and in the case of sash weights, are in many instances required to include a designation indicating the weight thereof. For these reasons cores of special form have been required which, up to the present time, have 15 been individually built up at a relatively great expense of time and labor. The object of the present invention is to provide a novel apparatus whereby the cores referred to may be produced in large quantities in an 20 efficient and uniform manner and with a minimum of physical effort. Other objects will appear from the description hereinafter and the features of novelty will be pointed out in the claims.

25 In the accompanying drawings, the invention is illustrated in a form adapted specially for the production of cores for use in casting sash weights, it being understood that this is not to define the limits of said 30 invention. In said drawings Fig. 1 is an elevation of the complete sash weight cast in accordance with the novel apparatus; Fig. 2 is a view looking at right angles to Fig. 1 showing the core still in connection with the 35 weight; Fig. 3 is a fragmentary view looking at right angles to Fig. 1; Fig. 4 is a sectional view of the core itself, on the line 4-4 of Fig. 3; Fig. 5 is a plan view of the major core box showing it in use; Fig. 6 is a sectional view on the line 6-6 of Fig. 40 5; Fig. 7 is a plan view showing a guide frame and scraper which form part of the apparatus; Fig. 8 is a sectional view on the line 8-8 of Fig. 7; Fig. 9 is a fragmentary 45 section on the line 9-9 of Fig. 8; Fig. 10 is a plan view showing the minor core box; Fig. 11 is a sectional view on the line 11-11 of Fig. 10; Fig. 12 is a sectional view illustrating the major and minor core boxes in 50 combination with each other for the production of the cores; Figs. 13 and 14 are perspective views of the major and minor cores respectively, and Fig. 15 is a similar view of the finished core.

55 For the purpose of clearness and because it is particularly adapted therefor, the invention is described in connection with the production of sash weights, it being understood, however, that the novel apparatus may be used, with equal efficiency, in other 60 branches of the casting art.

As shown in the drawings the apparatus includes a major core box consisting of a main plate 20 of metal or other heat resistant material of suitable shape and dimensions and provided with a plurality of main molding chambers 21 extending transversely through said plate as shown in Fig. 6. The chambers 21 are shaped, in accordance with the form of core to be produced and in 65 the illustrated example are provided with curved walls *a* and with converging walls *b*; the chambers 21 are arranged in groups over the surface area of the plate 20 and in one direction at least are located in alignment with each other in rows as shown in Fig. 5. In the direction in which they align with each other the chambers 21 of a given row are connected by means of upwardly 70 open channels 22 of predetermined surface 75 form as indicated in Fig. 6; the arrangement is such that the channels 22 in any given row are in registry with each other and form a continuous channel interrupted at intervals by the chambers 21 as illustrated 80 in Fig. 5. At opposite edges the plate 20 is provided with projections 23 extending outwardly and preferably provided with apertured bushings 24.

The apparatus further includes a guide 85 frame 25 shaped and dimensioned to fit upon the plate 20 in surface engagement therewith as shown in Figs. 7, 8 and 9. The guide frame 25 is provided with parallel slots 26 of a width corresponding to the width of the 90 channels 22 and of sufficient length to project beyond the terminal channels when the frame 25 is in place upon the plate 20; the slots 26 are positioned upon the guide frame 25 so as to register accurately with the channels 22 for the purpose to be more fully explained hereinafter. In order that the guide frame 25 may be easily combined with the plate 20 in the intended manner and maintained in proper position thereon, the frame 95 100 105 110 25 is provided with outwardly projecting lugs 27 carrying positioning pins 28 arranged to extend with the bushings 24 of the plate 20 as illustrated in Fig. 6. For use in combination with the guide frame 25 in a

manner to be more fully described herein-after, a scraper 29 is provided, and includes teeth or scraping members 30 located, dimensioned and shaped to fit the slots 26 and the channels 21 in the manner illustrated in Fig. 8.

In addition to the parts so far described, the apparatus includes a minor core box consisting of an auxiliary plate 31 of metal or other heat resistant material dimensioned and shaped to fit in surface engagement with the main plate 20 as shown in Fig. 12. The auxiliary plate 31 is provided with secondary molding chambers 32 shaped in a pre-determined manner to properly co-operate with the main chambers 21 and located so as to register therewith when the two plates are combined. The auxiliary plate 31 includes outwardly projecting ears 33 and positioning pins 34 extending perpendicularly therefrom for insertion into the bushings 24 to properly position the plates with respect to each other and to maintain them in such position.

If the sash weight or other casting, in its finished form, is intended to include a figure designating the weight of the casting or a designation indicating some other characteristic, a base plate 35 of suitable form and dimensions may form part of the apparatus. Upon its upper surface the base plate 35, in such case, is provided with molding or impression devices 36 of a character to produce the desired figures or other designations in the finished casting. The devices 36 may be directly produced on the base plate 35 as integral parts thereof, or attached in place thereon as independent elements; in any case the devices 36 are located so as to register with the secondary chambers 32 of the auxiliary plate 31 as shown in Fig. 10. To properly position and fix the plate 31 on the base plate 35, the latter may be provided with recesses 37 for the reception of the positioning pins 34.

In the production of cores for use in casting sash weights, such as illustrated in Fig. 1, it is customary to utilize a mixture of sand and linseed oil or other suitable binder, as the material for the cores, and to subject the molded cores to the action of heat to produce units of sufficient stability and cohesion to permit handling and yet capable of being easily crumbled to pieces when the casting operation has been finished.

When utilizing the apparatus illustrated and described herein for molding such cores, the main molding chambers 21 of the main plate 20 are filled with the core material *c*, the filling operation being performed in any convenient manner. In the preferred method, the main plate 20 is placed upon a supply of the core material and is manipulated back and forth in said supply to cause the plate to embed itself in the material and to cause the latter to work its way upwardly

into the chambers 21; this operation is continued until the latter, and perhaps even the channels 22, are filled with the material *c*, for instance, as shown in Fig. 6.

At this stage the guide frame 25 is placed in position upon the filled main core box with the pins 28 extending into the bushings 24; in this condition of the apparatus the slots 26 are in registry with the channels 22 and project beyond the main plate 20 at opposite ends as shown in Fig. 7. The scraper 29 is then placed in position upon the guide frame 25 with the scraping members 30 extending into the projecting portions of the slots 26; the scraper 29 is so proportioned that when it rests edgewise upon the plate 20, the members 30 will extend through the slots 26 into accurate registry with the channels 22 which they are dimensioned to fit as shown in Fig. 8. The scraper 29 is then moved along the guide frame 25 in the direction of the length of the slots 26 and thereby scrapes the core material *c* from the channels 22 and correspondingly scrapes such material from the main cores *d* in the chambers 21 to form upwardly open channels *e* in said cores as indicated in Figs. 7, 8 and 9. This scraping operation and the operation of filling the molding chambers 21 has packed the material *c* therein to an extent sufficient to fix the main cores *d* in said chambers against unintentional dropping therefrom; the character of the core material assists in the development of the slight surface adhesion and the cohesion necessary to maintain the main cores *d* in the chambers 21.

Either at this time or previously the secondary molding chambers 32 of the auxiliary core plate 31 have been filled with core material and placed upon the base plate 35 in order that impression *f* from the devices 36 may be made simultaneously in all of the auxiliary cores *g* as shown in Figs. 10 and 11. Any suitable method may be used to level off the upper end surfaces of the auxiliary cores *g* and to fix the latter against unintentional dropping from the chambers 32; it will be understood that the physical characteristics of the core material will here also assist in the development of the surface adhesion and the cohesion necessary to prevent unintentional dropping of the auxiliary cores *g* from the plate 31.

At this stage a multiplicity of main cores *d* with transverse upwardly open channels *e* are located in the main core plate 20, and a corresponding number of auxiliary cores *g* with the impressions *f* upon one surface thereof are located in the auxiliary core plate 31. The latter with its plurality of auxiliary cores *g* is now lifted from the base plate 35 and brought into surface engagement with the main core plate 20, the pins 34 being inserted into the bushings 24 to properly lo-

cate the plate 31 upon the plate 20 and to maintain it in place thereon. In this condition the auxiliary cores *g* are positioned over and in engagement with the main cores *d* with the impressions *f* in registry with and facing the channels *e* of said main cores as illustrated in Fig. 12. The combined plates 20 and 31 are then placed in an oven or equivalent device in order to subject the 10 cores to a heat action sufficient to bake the main and auxiliary cores and to unite them in the form of a unit as shown in Fig. 15. After the baking process has been completed the finished cores are removed from the 15 plates in any convenient manner and utilized in the conventional manner in the casting process. It will be noted that in the casting operation the channels *e* of the cores produce cross bars *h* in the finished weight 20 *i* and that the solid ends *j* of said cores produce eyelets *k*, the impression *f* meanwhile producing a corresponding figure or other designation *l* upon the end surfaces of the weights *i*. Because of the tapering form of 25 the core, a corresponding taper is given to the weight *i* as indicated at *m*. It will of course be understood that the character of the core will always be in accordance with the character of the casting which is to be 30 made. In any case, however, the operation of producing cores of the indicated class is reduced to the utmost simplicity and large numbers of cores may be coincidentally produced in a uniform and economical manner 35 and without the need for any specially skilled operators. After the casting of the weights or other elements has been completed, the combined cores *d*—*g* may simply be crumbled up and thereby removed from the 40 casting.

Various changes in the specific form shown and described may be made within the scope of the claims without departing from the spirit of the invention.

45 I claim:

1. In an apparatus for molding cores, a major core box provided with a plurality of main molding chambers located in a row, and having channels extending between said 50 chambers in alignment with each other.

2. In an apparatus for molding cores, a major core box provided with a plurality of main molding chambers located in a row, and having channels extending between said 55 chambers in alignment with each other, and a minor core box provided with a plurality of secondary molding chambers, said main and secondary chambers being arranged to independently mold main and auxiliary cores and being adapted to register with each other to combine said main and auxiliary cores.

60 3. In an apparatus for molding cores, the combination of a main core plate provided

with a plurality of molding chambers arranged in parallel rows, and having upwardly open channels extending between the chambers in each row in alignment with each other, a guide frame adapted to fit upon said main core plate and having a plurality of slots located for registry with said channels, and a scraping device movable lengthwise of said slots and fitting into said channels and movable diametrically across said chambers to form upwardly open channels 65 in the main cores therein. 70 75

4. In an apparatus for molding cores, the combination of an auxiliary core plate provided with a plurality of secondary molding chambers, a base plate arranged for surface engagement with said auxiliary core plate, and impression devices on said base plate arranged to register with said molding chambers. 80

5. In an apparatus for molding cores, the combination of a main core plate provided with a plurality of molding chambers arranged in parallel rows, and having upwardly open channels extending between the chambers in each row in alignment with each other, an auxiliary core plate provided with a plurality of secondary molding chambers and arranged to fit in surface engagement with said main plate, said main and secondary chambers being arranged to independently mold main and auxiliary cores and being adapted to register with each other to combine said main and auxiliary cores, apertured projections on one of said plates, and positioning pins on the other plate co-operating with said apertured projections to position the plates relatively to each other and to maintain them in such position. 90 95 100 105

6. In an apparatus for molding cores, the combination of a main core plate provided with a plurality of molding chambers arranged in parallel rows, and means movable diametrically across a plurality of said chambers simultaneously to concurrently groove the core material in said plurality of 110 chambers. 115

7. A core box for sash weight cores having a base forming section, a core loop forming ring section and a core loop forming base, the base forming section having a series of base forming apertures open at both ends, means adapted to close one end of each opening at the base, the core loop forming ring member having core loop forming openings and aligned openings intersecting the core loop forming openings, providing for the removal of the sand from the area between the aligned openings to form the holes in said core loops. 120 125

8. A core box for sash weight cores having a base forming section, a core loop forming ring section and a core loop forming base, the base forming section having a

series of base forming apertures open at both ends, a number support having numbers to register with the openings and adapted to close one end of each opening at the base, 5 the core loop forming ring member having core loop forming openings and aligned openings intersecting the core loop forming

openings, and a sweep adapted to enter said aligned openings and remove the sand from the centers of said apertures.

10

In testimony whereof I have hereunto set my hand.

ERNEST C. MOORHEAD.
